EDWARD P. GRIME, OF LOS ANGELES, CALIFORNIA, ASSIGNOR TO HOWARD W. STEPP,
OF WHITTIER, CALIFORNIA

DEVICE FOR HANDLING FLUID

Application filed June 5, 1929. Serial No. 368,636.

This invention has to do with a device for handling fluid, and relates more particularly to an ejector for raising fluid from a sump hole, or the like.

5 It is the general practice in the oil fields and in other situations to remove fluid from sump holes, or the like, by steam jet pumps or ejectors. As the sump holes are usually open holes, or pits formed in the ground, 10 there is generally a large quantity of foreign matter such as sticks of wood, rope, etc., in the fluid. The ejectors commonly used for this class of work are crude devices made of pipe fittings, and in practice they become 15 clogged with solid matter after a short period of use and do not always function properly. Further, these ejectors require priming each time they are used.

It is a primary object of this invention to 20 provide an ejector for removing fluid from a sump hole, or the like, that will not become clogged or filled with solid matter.

It is another object of the invention to provide an ejector of the type mentioned that 25 does not require priming.

Another object of the invention is to provide an ejector of the type mentioned that is of simple and improved construction and which is extremely cheap to manufacture.

30 The various objects and features of my invention will be best and more fully understood from the following detailed description of a typical, preferred form of the invention, throughout which description reference 35 is had to the accompanying drawings, in which:

Fig. 1 is a longitudinal or vertical sectional view of the ejector provided by this invention. Fig. 2 is an enlarged plan view 40 of one of the jets of the ejector, being a view taken as indicated by line 2-2 on Fig. 1.

The ejector provided by this invention includes, generally, a body A to be lowered into a sump hole, or the like, means L for lifting 45 or raising fluid into the body, means F for forcing the fluid upward out of the body, a manifold M to deliver fluid pressure to the nozzles L and F, means P in the body to trap fluid in the body so that the device is always 50 primed and ready for operation, and means

G to prevent solid matter from entering the body.

The body A of the ejector is in the form of an elongate hollow cylinder having an intake opening 10 at its lower end and a discharge opening 11 at its upper end. The body A is 55 preferably tapered upward and inward, being larger in diameter at its lower end than it is at its upper end. The openings 10 and 11 are directly opposite one another, the discharge opening 11 being directly above the intake opening 10, and being somewhat smaller in size than the intake opening 10. The discharge opening 11 is threaded to receive a 60 fluid conduit or pipe 12. The pipe 12 conducts the fluid handled by the ejector and may extend to any desired point. The central passage 13 extending through the body is relieved or enlarged at one side by a rounded 65 recess 14 formed in the wall of the body A. The recess 14 is formed in the body between the openings 10 and 11 and is preferably located relatively near the intake opening 10. The walls of the body may be of substantially 70 uniform thickness throughout. The body is preferably an integral unit or casting as shown in the drawings.

The means L provided to lift or raise fluid into the opening 13 of the body includes a nozzle 15 at the lower end of the body. The nozzle 15 may be attached to the lower end of the body at one side of the inlet opening 10 by cap screws 16, or the like. The nozzle 15 is in the form of a neck-like part extending 75 downwardly from the lower end of the body. The cap screws 16 extend through a flange 16^a 80 at the upper end of the nozzle and screw thread into the body A. The nozzle 15 is curved to extend transversely of the body so that its outer end is opposite or directly below the opening 10. The nozzle 15 has a passage 17 extending through it from the point of connection with the body to the outer end 85 which is opposite the opening 10.

Discharge openings 18 are provided in the nozzle 15 below the intake opening 10 to discharge upwardly into the passage 13 of the body. The nozzle 15 is formed and arranged so that fluid, say, steam, under pressure discharging from the openings 18 effectively 90 95 100

forces fluid into the body A. The discharge openings 18 are preferably small so that the fluid under pressure discharges from them at a high velocity.

5 The means F provided for forcing the fluid from the body A and through the pipe 12 includes a nozzle 20 disposed in the opening 13 of the body. The nozzle 20 may be formed integral with the body and is preferably located just above the recess 14. In the form of the invention illustrated, the lower part of the nozzle 20 forms the upper wall of the recess 14. An opening 21 extends through the nozzle 20 from one end to the other. The 10 nozzle 20 extends upwardly in the opening 13 and discharges upwardly in the center of the opening 18. A tip 22 may be provided on the nozzle, for instance, screw threaded into the opening 21 to extend upwardly to a point near 15 the top of the body. The tip 22 discharges upwardly at a point centrally located in the discharge opening 11. It will be obvious that other forms of jets or tips may be used instead of the openings 18 and the tip 22 without departing from the spirit of the invention. The tip 22 is positioned so that it discharges fluid under pressure at a point to effectively force fluid out through the conduit 12. The tip 22 discharges at the reduced upper end portion of the opening 13 so that the fluid is forced into the pipe 12 at a high rate 20 of speed.

The manifold M delivers fluid under pressure to the nozzles 15 and 20. In the form of 25 the invention illustrated the manifold M is located at one side of the body A and is preferably at the side of the body having the recess 14. The manifold is preferably formed integral with the body and the back wall of the recess 14 forms the inner wall of the manifold. The manifold M is provided with an inlet opening 27 at its upper end, the opening 27 being threaded to receive the supply pipe 28. The pipe 28 supplies steam or other fluid 30 under pressure to the manifold M. The manifold is divided into two branches, a branch 30 connected with the nozzle 15 and a branch 31 connected with the nozzle 20. The branch 30 extends to the lower end of the body A and registers with the passage 17 of the nozzle 15. The branch 31 extends directly into the nozzle 20, the two parts being formed integral. The manifold being formed in this manner, there is but one joint 35 or connection between the supply pipe 28 and the nozzles 15 and 20.

The means P, which automatically traps fluid in the body A when the flow of fluid through the nozzles 15 and 20 is stopped, 40 keeps the device primed for the next operation. This means includes a valve 32 carried within the body, and a valve seat 33 in the intake opening 10. The valve seat 33 is annular in form and is screw threaded into the opening 10. The opening 34^a in the seat ad-

mits fluid into the body. The top 34 of the seat 33 is flat and is finished to receive the valve 32. The seat ring 33 may be provided with grooves or notches 35 in the wall of the opening 34^a so that it can be readily engaged by a wrench, or the like.

70 The valve 32 is pivotally mounted and is carried within the opening 13 of the body. An arm 36 projects laterally from the valve and is carried by a pivot pin 37 held by a lug 38 on the wall of the opening 13. The valve 32 is mounted so that it is movable from a closed position where it is seated on the ring 33 to an open position in the recess 14. The valve 32 is in the form of a round disc or plate and has a flat sealing face 39 on its lower side to cooperate with the face 34 of the seat ring. The top of the valve is provided with a stop 40 which may be screw threaded into the valve and which engages the wall of the recess 14 to limit the opening movement of the valve. The valve is arranged so that the fluid discharged through the openings 18 holds it in the open position in the recess 14 and so that it automatically returns to the closed position by flow of fluid downwardly in the body. The stop 40 holds the valve 32 in a tilted open position away from the wall of the recess 14 so that the fluid flowing downwardly in the body A catches it and forces it closed. The head of fluid in the body and conduit 12 holds the valve closed when the device is not in use. The valve 32 may be counterbalanced so that it is easily operated to the open position. In the drawings I have shown a coil spring 41 extending between the top of the valve 32 and the wall of the recess 14 to counterbalance the weight of the valve.

100 The means G, provided to prevent solid matter or foreign material from entering the body of the ejector, consists of a plurality of strainer fingers or guards 43 arranged around the discharge openings 18 of the lifting nozzle. The guards 43 are provided to strain the fluid that enters the opening 34^a so that pieces of solid matter large enough to become caught in the device or to interfere with the functioning of the device cannot enter the body A. The guards 43 project upwardly from the top 44 of the nozzle 15 and are spaced a short distance apart. The guards are symmetrically arranged around the openings 18 and extend upwardly. The guards terminate close to the lower side of the seat ring 33. The guards may be curved as shown in Fig. 2 of the drawings and may be spaced to allow fluid to freely pass between them, but to prevent any large pieces of foreign matter from passing between them.

105 110 115 120 125 130 In operation fluid under pressure, preferably steam is passed through the supply pipe 28 and the manifold M and discharges through the openings 18 and the tip 22. When the ejector is not operating, the valve 32 is normally closed and the body A is filled

with fluid. The fluid or steam discharged through the openings 18 forces the valve open to the position shown in Fig. 1 of the drawings, and raises or lifts the fluid that is in the body into the pipe 12. The steam discharging through the tip 22 of the nozzle F forces the liquid through the pipe 12. The jet action of the steam discharging from the openings 18 draws fluid into the body through the opening 10. It will be apparent how the guards 43 strain the fluid as it enters the body and prevent large pieces of solid matter from entering the device.

The ejector provided by this invention is formed of a minimum number of parts and is inexpensive of manufacture. The manifold being formed integral with the body, makes the device compact and light. The upward convergence of the body causes the fluid passing through it to increase in speed so that it enters the pipe 12 at a very high velocity.

Having described only a typical, preferred form of my invention, I do not wish to limit myself to the specific details set forth, but wish to reserve to myself any changes or variations that may appear to those skilled in the art or fall within the scope of the following claims.

30 Having described my invention, I claim:
1. A device of the character described including, a body having an inlet opening, a fluid pressure jet discharging at a point below the body for lifting fluid into the body, 35 a fluid pressure jet discharging in the upper portion of the body for forcing fluid from the body, a valve for automatically trapping fluid in the body upon the discharge of fluid from the first-mentioned jet stopping and 40 normally held open by the fluid pressure from said jet, and a spring for counter-balancing the valve.

2. A device of the character described, including a body having a central longitudinal 45 opening open at its lower end, a nozzle discharging upwardly into the lower end of the body opening from a point spaced below the lower end of the body for lifting fluid into the body, jet means in the body for forcing 50 fluid from the body, guards projecting upwardly from the discharge of the nozzle to a point adjacent the lower end of the body, and a valve for automatically trapping fluid in the body upon the discharge of fluid from 55 the nozzle stopping.

In witness that I claim the foregoing I have hereunto subscribed my name this 13th day of May, 1929.

EDWARD P. GRIME.
